UNITED STATES PATENT OFFICE.

HERMAN C. BESTE, OF BALTIMORE, MARYLAND.

MEANS FOR APPLYING CROWN-SEALS.

1,341,163.

Specification of Letters Patent. Patented May 25, 1920.

Application filed September 23, 1919. Serial No. 325,753.

To all whom it may concern:

Be it known that I, HERMAN C. BESTE, a citizen of the United States, residing at Baltimore, State of Maryland, have invented certain new and useful Improvements in Means for Applying Crown-Seals, of which the following is a specification.

This invention relates to a simple means for applying crown seals to bottles and for removing the same therefrom. It also relates to a method of re-capping bottles with used crown seals.

It is an object of the invention to provide a simple device, for household use, whereby crown seals may be applied to bottles and the like, thus obviating the use of unsatisfactory methods of sealing bottles, jars and the like, with corks.

A most important object of the invention is to provide a device whereby previously used crown seals may be re-applied as satisfactorily as new ones, thus old caps may be saved and used over again or, if a bottle of some beverage is opened and all of the contents not used, then the cap may be re-applied as tight as originally and the remaining beverage preserved.

A further object is to relate the devices above-mentioned in such manner that they form a means for removing a crown seal and thus the invention provides a household utensil as convenient as the usual cork-screw or can-opener.

Other and further important objects of the invention will be apparent from the disclosure in the drawings and specification.

The invention (in a preferred form) is illustrated in the drawings and hereinafter more fully described.

40 In the drawings:

Figure 1 is a view in side elevation partly broken away and showing the invention in the act of expanding a previously used cap.

Fig. 2 is a view in side elevation partly broken away and showing the invention in the act of applying the cap to a bottle.

Fig. 3 is a view in side elevation showing the invention in the act of de-capping a bottle.

50 Fig. 4 is an end view showing the expanding means; and

Fig. 5 is an end view showing the compressing means.

As shown in the drawings:

The invention comprises an expanding head 1 and a cap compressing head 2 connected by a stem 3. The expanding head 1 is provided with a tapered face 4 which is of sufficient size to expand the crimped skirt 5 of the usual crown seal 6 so that it will fit easily down onto the bead 7 of a bottle 8. To expand the crown seal the same is placed upside down on a table, or other hard surface, as shown in Fig. 1, and the tapered head or plug 1 is driven into the cap by the blow of a hammer 9 thus expanding the crimped skirt 5.

To apply the seal 6 to the bottle, it is placed on the bottle bead as shown in Fig. 2, and the compressing head 2 is placed over it and the device tapped again with the hammer 9 as shown. The compressing head has a tapered recess 10 which is fluted, as shown in Fig. 5, so that the flutes fit the crimps of the seal and as the head 2 is forced down onto the seal it carries the seal onto the bead 7 of the bottle and crimps the seal in place in the same tight manner as originally applied.

The rear edge of the expanding head 1 is slightly flared as shown at 11 so that it will catch over the edge of a crown seal as shown in Fig. 3, and the compressing head 2 then rests on the seal and forms a fulcrum so that by lifting in the direction indicated by the arrow the cap may be removed.

I am aware that various details of construction may be varied through a wide range without departing from the principles of this invention, and I therefore do not propose limiting the patent granted otherwise than necessitated by the prior art.

I claim as my invention:

1. A capping and decapping tool having cap expanding and applying ends, one of said ends having means to engage the cap for removal of the same and the other forming a fulcrum and handle during removal.

2. A capping and decapping tool having cap expanding and applying ends, one of said ends having a lipped edge to engage the cap for removal, the other end forming a fulcrum and handle during removal.

HERMAN C. BESTE,
